UNITED STATES PATENT OFFICE.

ROBERT EDGAR, OF NEW YORK, N. Y.

WASHBOILER ATTACHMENT.

Application filed July 2, 1921. Serial No. 482,083.

To all whom it may concern:

Be it known that I, ROBERT EDGAR, a citizen of the United States, residing at the city of New York, borough of Manhattan, in the county and State of New York, have invented a certain new and useful Washboiler Attachment, of which the following is a specification.

This invention is a wash boiler attachment of that general type adapted to be positioned interiorly of a wash boiler for the purpose of effecting therein an automatic circulation of the water over the clothes being washed.

10 Numerous devices have heretofore been suggested for accomplishing the general purposes under consideration, but, so far as applicant is aware, none of them have gone into general or extensive use.

20 The present invention is simple in construction, economical to manufacture, and, in practice, has been demonstrated to efficiently and successfully accomplish its intended functions, in that it not only thoroughly 25 cleans the clothes under treatment, but does so in a comparatively short time and with a minimum requirement of soap or other detergent, and, yet, without in anywise injuring the fabrics.

30 The accompanying drawings illustrate different forms of the preferred, practical embodiment of the invention, but the constructions shown therein are to be regarded as typical, only, and not exclusive of the 35 different forms in which the invention may be given practical expression or embodiment.

Figure 1 is a perspective view of one form 40 of the attachment or device, separate from the boiler, and wherein is embodied a slide valve which I prefer, but do not necessarily, employ.

Figure 2 is a perspective view taken on line 2-2 of Figure 1, showing the attachment 45 operably positioned within a wash boiler, and

Figure 3 is a fragmentary perspective view, from beneath, of the preferred form of the inlet mouth of the attachment.

50 Referring to the drawings, 1 designates a wash boiler, in conventional form, 2 the base chamber of the attachment, which is bottomless and adapted to rest on the floor of the boiler with its top member 3 forming 55 a support for the clothes being washed. As clearly appears from the drawings, the top

member 3 of the base chamber is inclined, intermediate the ends thereof, and has its front edge turned upon itself, so as to form an inclined water deflecting surface 4. Secured to the bottom of said inturned edge, see Fig. 3, are a plurality of U-shaped members 6, which support said inturned edge and rest upon the bottom of the boiler and provide an inlet mouth to chamber 2. 60 These U-shaped members serve the function of dividing up the inflowing stream of water. In order to preclude the clothes from being drawn into chamber 2 by the current of inflowing water, or to preclude the inlet to 65 said chamber from being clogged by the clothes, it is preferred to employ a mouth guard embodying, as shown in Fig. 3, a net work of wire, or other foraminous structure. The horizontal portion 7 of the guard is secured to the bottom of the inturned edge of member 3, and the vertical portion 8, extends downwardly therefrom forming an effective guard to the inlet mouth of chamber 2. 70 75

In the other form of inlet mouth to chamber 2, illustrated in Figs. 1 and 2, a corrugated member 9 is attached below the inturned edge of member 3, thereby providing an inlet to chamber 2 beneath said corrugated member with the spaces 10 in the corrugated member forming water inlets to said chamber. 80 85

At the rear or enlarged side of chamber 2 is a riser 11, the top of which extends substantially to the top of the boiler and so fashioned as to form an exit or outlet mouth 12 for the water which rises therein, whereby the steam is forcibly ejected and distributed over the top surface of the clothes in 90 the boiler. 95

The riser 11 is preferably provided, intermediate the top and bottom thereof, with a supplementary opening, which may partake of the form of a series of perforations 100 or holes 13, whereby, when it is desired, for example, to wash one half a boiler full of clothes, the circulating water is discharged through the openings 13, rather than through the exit 12. The openings 105 13 may be sealed or unsealed by the manipulation of a slide valve or member 14, operating in guides 15, so that if it is desired to uncover said openings, the valve 14 is removed from the attachment before inserting 110 said attachment in the boiler, whereas, if it is not desired to employ the openings 13, but,

to use the exit 12, then the slide member or valve 14 is maintained in position to seal the holes 13.

From the foregoing description of the invention, its operation will be clear, but it may be briefly described as follows. Upon the water in the boiler being elevated to sufficient temperature, the steam produced naturally has a tendency to rise, as does likewise the hot water, thereby producing a rapid flow of the water in the riser 11 which is forcibly ejected through the exit outlet 12 and distributed over the upper surface of the clothes, whereupon it seeps downwardly through the clothes by gravity, enhanced by the natural suction of the water entering the inlet mouth to chamber 2. The tendency of the water in chamber 2 to rise upwardly, coupled with the inclined shape of the chamber, causes more or less water to be thrown against chamber 4 formed by the inturned edge of top member 3, whence it is deflected rearwardly of the chamber, thereby very materially increasing the suction at the inlet mouth of the chamber and resulting in a more positive and rapid circulation of water through riser 11, as described.

During the washing operations, the cover is naturally tightly secured to the boiler, thereby precluding all escape of steam and enhancing pressure within the boiler. The device is relatively compact and, in practice, need not take up more than one fifteenth of the boiler space, and, of course, may be made to fit various sizes of boilers. It will be noted that all the centre space of the boiler is left free, whereby clothes may be introduced or removed from the boiler without obstruction from the attachment.

It will be understood that formal changes may be made in the structure described,

such as the substitution of equivalents, without departing from the spirit or substance 45 of the invention, the scope of which is commensurate with the appended claims.

Having described my invention, what I claim as new and desire to secure by Letters Patent is:

1. A wash boiler attachment embodying a chambered base in the form of a shell adapted to fit into a wash boiler, said shell having an inclined top, and open bottom, and an inlet mouth at the lower side thereof 55 and extending along the greater portion of the length of said side, a downwardly and inwardly curved flange positioned above and forming the upper boundary of the mouth and constituting a deflecting member, and a 60 riser associated with the high side of the shell, said riser being in communication with the interior of the shell at its bottom and being provided at its top with a discharge mouth pointing in a lateral direction and of substantially the same length as the inlet mouth, whereby water is drawn through the inlet mouth and exhausted through the discharge mouth when the bottom of the boiler is heated.

2. A wash boiler attachment embodying a chambered base in the form of a shell adapted to fit into a wash boiler, a riser extending upwardly from the top of the shell and provided at its top with a discharge mouth, the top of the shell being sloped downwardly away from the base of the riser, an inlet mouth at the side of the shell and extending along the greater portion of the length of said side, and a 75 downwardly and inwardly curved flange positioned above and forming the upper boundary of the inlet mouth.

In testimony whereof I have signed the foregoing specification.

ROBERT EDGAR.
